Primary Examiner — Darcey E Gottschalk*(74) Attorney, Agent, or Firm* — Harness, Dickey & Pierce, P.L.C.; Anthony G. Fussner(57) **CLAIM**

The ornamental design for an adapter for a beverage container thermal insulator, as shown and described.

DESCRIPTION

FIG. 1 is a perspective view of an adapter for a beverage container thermal insulator showing my new design; FIG. 2 is an elevation view of the adapter shown in FIG. 1; FIG. 3 is a top plan view of the adapter shown in FIG. 1; FIG. 4 is a bottom plan view of the adapter shown in FIG. 1; and,

FIG. 5 is a perspective view showing the adapter shown in FIGS. 1 to 4 being used with a 12-ounce slim can and a stainless steel can cooler.

In the drawings, the details shown in broken lines depict environmental subject matter only and form no part of the claimed design.

1 Claim, 5 Drawing Sheets(56)
